UNITED STATES PATENT OFFICE.

ALFRED H. McCULLOCH, OF BOSTON, MASSACHUSETTS, ASSIGNOR OF ONE-HALF TO
LAURENCE McCULLOCH, OF SPRINGFIELD, MASSACHUSETTS.

FURNACE-REGULATOR UNIT.

Application filed November 22, 1926. Serial No. 149,879.

The invention to be hereinafter described relates to a damper and air-inlet regulator unit for application to the pipe for conducting the gases of combustion from a furnace, 5 and is an improvement upon a draft regulator of the type disclosed in Letters Patent of the United States No. 116,675, granted to Nathaniel A. Boynton, July 4, 1871.

The regulator of said patent comprises a 10 head having a collar curved to conform to the contour of the pipe. Projecting through a bearing in the head is a shaft having a disk-shaped damper at one end thereof and a handle at the opposite end thereof. Secured to the shaft is a sleeve having diametrically opposed segmental-shaped wings or plates projecting therefrom adapted to cover and uncover openings in the head. The construction is such that when the handle 15 is grasped and the damper is adjusted to open position for full draft from the furnace, the wings cover the openings in the head, and on the other hand, when the damper is adjusted to closed position, the 20 wings uncover the openings in the head. The wings uncover the openings in the head.

The regulator of said patent has been on the market for many years, and has been popular, due among other reasons, to its simplicity and cheapness of construction and 25 the fact that it may be quickly and easily applied to the pipe. However, there is a serious defect in said regulator, in that it is so constructed that when the damper in the pipe is closed, the openings in the head allow noxious and injurious gases coming 30 from the furnace to escape into the cellar in which the furnace is located, and rise up through the building to the discomfort of the occupants thereof. This condition has 35 been aggravated in recent years due to increase in use of fuels which produce greater quantities of smoke and gas.

The aim and purpose of the present invention, therefore, is to provide a regulator 40 which will retain the substantial advantages of the regulator of the Boynton patent, but will overcome the objection thereto referred to.

The character of the invention may be 45 best understood by reference to the following description of an embodiment thereof shown in the accompanying drawings, wherein:

Fig. 1 is a sectional view of the regulator

unit and a portion of a pipe to which it is 55 applied;

Fig. 2 is a transverse section taken on line 2—2 of Fig. 1;

Fig. 3 is a side elevation of the regulator unit and pipe, the damper being indicated 60 by dotted lines in closed position;

Fig. 4 is a view of parts shown in Fig. 3, the damper being indicated by dotted lines in open position;

Fig. 5 on a smaller scale is a front view of 65 the head showing the location of the air-inlet opening therein; and

Fig. 6 is a front view of the wing plates.

Referring to the drawings, 1 designates a portion of the pipe for conducting the 70 gases of combustion from a furnace toward a chimney. To this pipe is applied a regulator unit embodying the invention comprising a head 3 provided with a collar 5 curved to conform to the contour of the pipe and 75 having a flange 7 secured by stove bolts 9 to the marginal portion of the pipe surrounding a hole 11 cut in the pipe and of a size conforming to the collar.

At the center of the head is a short bearing 13 in which is mounted a shaft 15 having mating spliced parts 17 and 19 secured together by a cotter pin 21 entered through registering bores in said parts. Formed integral with the shaft part 17 is a disk-shaped 80 damper 23 located in the pipe, and in the present instance has a diameter somewhat less than the internal diameter of the pipe. Formed integral with the shaft part 19 is a handle 25 adapted to be grasped to adjust the 85 damper as more fully hereinafter described.

The shaft 15 extends through a sleeve 27 having diametrically opposed segmental-shaped wings or plates 31 and 33 projecting therefrom and integral therewith. The 90 cotter pin 21 referred to also extends through registering bores in the sleeve and serves to secure the sleeve to the shaft.

The head 3 has a segmental-shaped air-inlet opening 35 therein which is located wholly at the chimney side of the damper. The wings 31 and 33 engage the outer face of the head, and the wing 31 is adapted to cover and uncover the air-inlet opening 35. Projecting from the head is a stop 37 adapted to be engaged by an edge of the wing 31 when the latter is in closed position. A notch 39 in the wing 33 is adapted to engage 100 105

the stop when the wing 31 is in open position. The shaft has a circumferential flange 41 which engages one side of the head, and the inner end of the sleeve 27 and the wings 5 engage the opposite side of the head, thereby to confine the shaft against axial movement in the bearing.

The parts of the regulator described may all be castings with the exception of the 10 stove bolts and the cotter pin, and no machining of parts is required. The parts may be quickly and easily assembled. To accomplish this, it is merely necessary to insert the shaft part 17 in the bearing, and pre- 15 sent the sleeve 27 carrying the wings to the head, the inner diameter of the sleeve being sufficiently large to fit freely over the bearing. The shaft part 19 is inserted in the sleeve, and the cotter pin is passed 20 through the bores in the sleeve and shaft parts, thereby to secure them together.

The wings 31 and 33 are substantially the same size and weight. While only the wing 31 serves as a cover for the air-inlet opening 35, yet the other wing 33 serves useful purposes. It counterbalances the cover wing, it cooperates with the cover wing in engaging the head to maintain the shaft in axial alignment with the bearing, thereby prevent- 30 ing sagging of the damper from its proper position in the pipe. It is desirable that a short bearing shall be employed, and since there is only one bearing it is essential to provide means for maintaining axial alignment of the shaft with the bearing. This is 35 accomplished in the present construction by simple means which in addition to this function has other useful purposes.

When it is desired to apply the regulator 40 unit to the pipe, the cotter pin is removed to allow separation of the parts. A hole is cut in the side of the pipe of appropriate size, and the collar is secured by the stove bolts to the marginal portion of the pipe sur- 45 rounding the hole. Then the damper is introduced into the pipe and the shaft part 17 is inserted through the bearing, the sleeve carrying the wings is presented to the head, the shaft part 19 is inserted into the sleeve, 50 and the cotter pin is passed through the registering bores to secure the sleeve and the shaft parts together.

In use, when a strong draft in the furnace 55 is desired, the handle is grasped and the damper is rotatively adjusted to a position in which it is parallel to the length of the pipe, as indicated in Fig. 4. When the damper is adjusted to this position, the wing 31 will cover the air-inlet opening 35 and 60 an edge of said wing will engage the stop 37. When it is desired to check the fire and hold the heat in the furnace, the handle is grasped and the damper is rotatively adjusted to a closed position in which it extends trans- 65 versely to the length of the pipe, as indi-

cated in Figs. 1, 2 and 3. When the damper is in this position, the wing 31 uncovers the air-inlet opening 35 and the wing notch 39 engages the stop 37. This will allow air in the cellar or other place in which the furnace is located to enter the pipe through the air-inlet opening in the direction of the curved arrow (Fig. 1).

It may be assumed that 43 (Fig. 1) is the 75 side of the pipe between the furnace and the damper, and 45 is the side of the pipe between the chimney and the damper, and the draft is in the direction of the straight arrow (Fig. 1). The air-inlet opening 35 is located wholly at the chimney side of the 80 damper. The head is closed throughout with the exception of said opening. Therefore when the damper is in closed position none of the gases of combustion at the furnace 85 side of the damper can escape through the regulator unit into the cellar.

In the regulator of the Boynton patent, on the other hand, the diametrically opposed 90 openings in the head are so formed and located that when the damper is closed, portions of both of said openings are open at the furnace side of the damper, thereby allowing the noxious objectionable gases, coming from the furnace, to escape from the 95 pipe into the cellar. By the regulator disclosed herein this defect is overcome.

The damper and wing plates have a balanced construction and their construction and mounting are such that they will remain 100 in any position to which they are adjusted. The weight of the parts and the friction between the wings and the face of the head contribute to this effect. The damper may be set at any angle, and the wing 31 may 105 partially cover the air-inlet opening to any extent desired. The regulator unit is shown herein applied to a horizontal pipe, but it can equally well be applied to a vertical pipe or to a pipe having any inclination. The 110 regulator unit is simple and strong in construction, cheap to manufacture, not liable to get out of order, and able to withstand high temperatures.

I claim as my invention:

1. The combination of the pipe for conducting gases of combustion from a furnace, and a damper and air-inlet regulator unit for application to the pipe comprising a head having a collar secured to the marginal portion of the pipe surrounding a hole 115 in the side of the pipe, said head having a short bearing therein, a shaft projecting through said bearing having a handle at one end thereof and a damper at the opposite end thereof located in the pipe and movable 120 to and from a closed position in which it is transverse to the length of the pipe, said head having an air-inlet opening wholly at the chimney side of the damper, and a pair 125 of diametrically opposed wing plates se- 130

- cured to the shaft, one of said plates being adapted to cover the air-inlet opening when the damper is open and to uncover said opening when the damper is closed, and the other 5 of said plates being adapted to counterbalance the cover plate, said plates being adapted to engage the face of the head and maintain the shaft in axial alinement with its bearing.
- 10 2. A damper and air-inlet regulator unit for application to the pipe for conducting gases of combustion from the furnace, comprising a head having a collar curved to conform to the contour of the pipe and adapted 15 for attachment thereto, said head having a single air-inlet opening therein, a bearing at the center of the head, a shaft projecting through the bearing, a damper on the shaft for regulating the draft through the pipe, a handle 20 on the shaft, a flange on the shaft on one side of the head, and a pair of counterbalanced wing plates secured to the shaft at the opposite side of the head, said flange and plates cooperating with the head to confine the shaft against axial movement and to 25 maintain the shaft in alinement with the bearing, said air-inlet opening being at the chimney side of the damper, and one of said plates being adapted to cover the air-inlet opening on adjustment of the damper to 30 open position and to uncover said opening on adjustment of the damper to closed position.
3. A damper and air-inlet regulator unit for application to the pipe for conducting 35 gases of combustion from a furnace, comprising a head having a collar adapted for attachment to the pipe, a bearing in said head, a shaft projecting through the bearing, a damper on the shaft for regulating 40 the draft through the pipe, a handle on the shaft, said head being closed throughout excepting an air-inlet opening located in the head at the chimney side of the damper, and a wing plate secured to the shaft movable 45 over the outer face of the head to cover and uncover the air-inlet opening.

ALFRED H. McCULLOCH.
